UNITED STATES PATENT OFFICE.

FORREST A. TURNER, OF ANSON, TEXAS.

PRESSED-METAL WHEEL.

Application filed November 9, 1927. Serial No. 232,132.

This invention relates to wheels designed chiefly for motor vehicles and supplies an article of the nature aforesaid which is light, strong, durable and economical in manufacture.

The invention provides an essentially sheet metal wheel which may be pressed or similarly formed, the spoke members being welded, riveted, or otherwise secured to the body of the wheel.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is a side view of a vehicle wheel embodying the invention, a portion of the band or rim being broken away.

Figure 2 is an enlarged sectional view on the line 2—2 of Figure 1.

Figure 3 is a perspective view of one of the spoke members.

Figure 4 is a detail view of a portion of the body of the wheel showing an integral spoke section.

Figure 5 is a detail sectional view on the line 5—5 of Figure 1.

Corresponding and like parts are referred to in the following description and designated in the several views of the drawing by like reference characters.

The numeral 1 designates the body of the wheel which consists of a disk of sheet metal of determinate size depending upon the nature of the wheel. The body 1 is provided about its outer edge with projections 2 which form outer sections of the spokes. The projections 2 form a part of the body and are disposed in the plane thereof. The central portion of the body 1 is cut away to provide an opening 3 for the reception of a hub of any determinate make or construction depending upon the finish of the wheel.

Spoke members 4 are provided and are attached to the body 1 and parts 2 in any preferred way, as by welding, riveting, or in a manner best adapted to existing condi-

tions. The spokes 4 are hollow and taper throughout their length, as indicated most clearly in Figure 3. The spokes are closed upon three sides and are arranged with the open side adjacent the body 1 and projections 2. The spokes are reversely curved, being of O.G. outline in the direction of their length. Lugs 5 are formed at the outer end of the spokes and are adapted to pass through openings formed in the rim 6 which is secured in place by upsetting the projecting ends of the lugs, as indicated most clearly in Figure 2. The spokes are of a length to extend from a point adjacent the opening 3 to the inner side of the rim 6, it being understood that the inner side of the wheel is flat, whereas the spokes appear upon the outer side to present a finish. It is observed that the wheels are provided in rights and lefts so that the spokes may curve in the same direction and appear upon the outer side of the wheel.

When the band or rim 6 consists of an integral annulus the parts are assembled preliminary to securing the spokes to the body of the wheel, so that the lugs 5 may be passed through the openings formed in the rim for their reception.

Having thus described the invention, I claim:

1. A metal wheel consisting of a flat body, spokes placed against a side of the body and secured thereto, and having their outer ends projecting some distance beyond the outer edge of the main portion of the body, and a rim connecting the projecting ends of the spokes.

2. A metal wheel comprising a metal disc having projections about the outer edge and in the plane of the disc, hollow spoke members arranged with their hollow sides against the disc and the projections thereof to which they are attached, and a rim connecting the projecting end of the spokes.

3. A metal wheel comprising a disc having projections about its outer edge, and in the plane of the disc, hollow spokes reversely curved and tapering throughout their length and arranged with the hollow side adjacent the disc and the projections thereof, said spokes having integral lugs at their outer ends, and a rim secured to the projecting ends of the spokes by means of said lugs.

In testimony whereof I affix my signature.

FORREST A. TURNER. [L.S.]
